CLAIM

The ornamental design for an air conditioner unit screening device, as shown and described.

DESCRIPTION

FIG. 1 is a rear elevational view of an air conditioner unit screening device showing my new design;

FIG. 2 is a front elevational view thereof;

FIG. 3 is a left side elevational view thereof;

FIG. 4 is a right side elevational view thereof, with the broken-line disclosure being for illustrative purposes only and forming no part of the claimed design;

FIG. 5 is a top plan view thereof;

FIG. 6 is a bottom plan view thereof; and,

FIG. 7 is a top, front, and right side perspective thereof.
